Louis Ludwig, New York, N.Y. (½ Eagle Electric Mfg.
Co., 23-10 Bridge Plaza S., Long Island City, N.Y.)

Filed Jan. 17, 1962, Ser. No. 68,342

Term of patent 14 years

(Cl. D48—20)

FIG. 1 is a side elevational view of a night light showing my new design;

FIGS. 2 and 3 are top and bottom plan views respectively of said night light; and

FIGS. 4 and 5 are left-end and right-end elevational views respectively of said night light.

The dominant features of my design reside in the portions shown in full lines.

I claim:

The ornamental design for a night light, substantially as shown and described.
